UNITED STATES PATENT OFFICE.

WILFRED G. COLES, OF MADISON, WISCONSIN, ASSIGNOR TO MADISON KIPP CORPORATION, OF MADISON, WISCONSIN, A CORPORATION OF WISCONSIN.

OIL-CUP.

1,338,554.

Specification of Letters Patent. Patented Apr. 27, 1920.

Application filed December 16, 1919. Serial No. 345,217.

To all whom it may concern:

Be it known that I, WILFRED G. COLES, a citizen of the United States, residing at Madison, in the county of Dane and State of 5 Wisconsin, have invented certain new and useful Improvements in Oil-Cups, of which the following is a specification.

This invention pertains to oil cups and in certain particulars is an improvement 10 upon that set forth and claimed in Letters Patent No. 1,262,981, dated April 16, 1918.

The present structure, as in the former case, partakes of the form of an oil-cup in 15 which there is mounted a pump or plunger 15 which, when actuated, serves to force the lubricant past a valve and to a point where it is to be utilized.

The object of the present invention is to 20 simplify the structure and to provide means whereby the leakage of lubricant between the cap or closure of the body is prevented.

The structure is illustrated in the annexed drawings, wherein,—

Figure 1 is a vertical sectional view of the 25 cup with the piston lowered; and

Fig. 2 a sectional elevation showing the piston raised preparatory to forcing a charge of lubricant from the cup.

The cup or reservoir is designated by 1 30 and is provided with a reduced cylindrical neck portion 2, from which projects a further extension 3 which is reduced and exteriorly threaded, the lower end thereof being inturned and provided with a central discharge opening 4. The upper end of the cup is smaller in diameter than the body of the cup, as at 5, and is exteriorly threaded, the threaded portion merging into the body 35 forming a seat 6.

The cap or closure is designated by 7 and 40 is provided at its lower end with an outwardly flaring lip or skirt 8, the inner face of which, when the cap is screwed down, makes a tight fit with the underlying face 6, 45 the skirt and face forming, in effect, a seat and valve. This arrangement prevents any leakage between the parts and the entrance of water into and through the joint. The cap is provided with a central hub 9 through 50 which the stem 10 passes, the stem at its lower end carrying a piston or plunger 11. The stem at its upper end has attached thereto an operating handle 12, and a spring 13 encircling the stem and bearing at its ends 55 on washers 14 and 15 tends to force the pis-

ton rod downwardly. A flexible washer 16 lies between washer 15 and the inner face of the cap or closure 7 and prevents leakage of lubricant outwardly along the stem or rod 10.

A combined cylinder and piston guide is mounted within the lower portion of the reservoir, and the same is formed of a single piece of metal 17, the lower end whereof makes a driving fit with the interior portion of the neck section 2. Said member extends upwardly within the reservoir and is provided with lateral ports 18 which open into the reservoir immediately adjacent the lower downwardly inclined wall 19 thereof.

The lower end of the cylinder is counterbored and internally threaded and a stop collar 20 for the piston is screwed thereon. Said collar also provides a seat at its lower end against which bears a non-return valve 21, the valve being normally held to its seat by a spring 22, the lower end of which bears against the inturned end of the threaded extension 3.

In operation the reservoir is filled with 80 lubricant and the cap screwed to place, the outturned lip 8 taking a fair bearing against the seat 6 and producing a tight joint. Upon an outward movement of the handle 12, piston 11 is raised and the lubricant 85 passes into the cylinder through ports 18, filling the same. The handle is then released or forced inward manually and the descending piston forces the lubricant from the cylinder through collar 20 unseating the 90 valve 21 and is finally discharged through port 4 to the part to be lubricated.

The construction as above outlined is at 95 once simple and strong and may be readily produced. It affords a minimum number of exposed joints and hence minimizes leakage and may be readily kept clean.

What is claimed is,—

1. In a lubricator, the combination of a cup or reservoir formed from a single piece 100 of metal drawn to form and presenting a reduced lower end; a cylinder mounted within the reservoir, the lower portion whereof makes a driving fit within said reduced end, said cylinder being ported into 105 said reservoir; a piston mounted in the cylinder; a cap for the reservoir; and a stem extending from the piston through the cap.

2. In a lubricator, the combination of a 110 cup or reservoir having an annular inwardly

inclined seat formed adjacent its upper end, said end being externally threaded; a cap therefor, said cap having an outwardly flaring lip coöperating with said seat; and 5 means mounted within the reservoir for forcing lubricant therefrom.

3. In a lubricator, the combination of a cup or reservoir formed from a single piece of metal drawn to form and providing a 10 body portion, an upper portion of smaller diameter with an inclined seat formed between the body and upper portion, and a relatively small cylindrical portion extending downwardly from the body; a combined 15 cylinder and piston guide the lower part whereof is seated and held within the cylindrical portion; a piston mounted for reciprocation therein; and a cap having an outwardly flaring lip at its lower end adapted 20 when the cap is screwed in place to contact the inclined seat aforesaid and to make a tight fit therewith.

4. In a lubricator, the combination of a cup or reservoir formed from a single piece 25 of metal drawn to form and providing a body portion, an upper portion of smaller diameter with an inclined seat formed between the body and upper portion, and a relatively small cylindrical portion extending 30 downwardly from the body; a combined cylinder and piston guide the lower part whereof is seated and held within the cylindrical portion; a piston mounted for reciprocation therein; a collar mounted in the 35 lower end of said cylinder member; a valve;

a spring urging said valve against said member; and a cap having an outwardly flaring lip at its lower end adapted when the cap is screwed in place to contact the inclined seat aforesaid and to make a tight 40 fit therewith.

5. In a lubricator, the combination of a cup or reservoir formed from a single piece of metal drawn to form, said member presenting an upper externally threaded section, 45 an annular outwardly inclining seat, a body portion proper, an inwardly and downwardly inclining bottom, a relatively narrow cylindrical shaped section extending downwardly from the bottom and an 50 externally threaded still smaller projection; an internally threaded cap having an outwardly flaring lip adapted to contact the seat aforesaid; a combined piston guide and cylinder, the lower end whereof makes a 55 driving fit within the cylindrical shaped section of the cup, said member having lateral ports opening into the cup; a piston mounted in said combined cylinder and guide; a stem extending upwardly therefrom and 60 passing through an opening formed centrally of the cap; a collar seated in the lower end of the cylinder; a valve; and a spring urging the valve against the lower 65 face of the collar to close the opening therein.

In testimony whereof I have signed my name to this specification.

WILFRED G. COLES.
